UNITED STATES PATENT OFFICE

WALTER A. GOERTZ, OF EAST ORANGE, NEW JERSEY, ASSIGNOR TO AUGUST GOERTZ & CO., INC., A CORPORATION OF NEW JERSEY

VANITY BOX

Application filed October 18, 1929. Serial No. 400,578.

This invention relates, generally, to improvements in vanity boxes or compacts for carrying cosmetic materials.

The invention has for its principal object to provide a novel construction of vanity box or compact comprising body sections arranged to close one upon the other, one of said sections having a retaining frame therein, said retaining frame being constructed and arranged to pivotally support a novel swivel lip-stick therein in addition to other cosmetic agencies, said swivel lip-stick being easily turned outwardly of said retaining frame and its body section to facilitate the convenient use thereof.

Other objects of this invention not at this time more particularly enumerated will be clearly understood from the following detailed description of the same.

10 The invention is clearly illustrated in the accompanying drawings, in which:—

Fig. 1 is a plan view of a vanity box made according to and embodying the principles of this invention, the body sections thereof being shown in open relation;

Fig. 2 is an enlarged transverse sectional view taken along line 2—2 of Fig. 1;

Fig. 3 is a longitudinal sectional view with parts broken away, taken along the central axial line of the vanity box, but illustrates the lip-stick receiving socket as pivotally mounted adjacent the hinged connection of the mirror with the lower body section instead of adjacent the hinged connection of the upper body section with the lower body section as shown in Figs. 1 and 2, and illustrates in dotted lines, the lip-stick cover swung partially outwardly of the body section with the lip-stick removed therefrom;

Fig. 4 illustrates certain features of construction of the novel vanity box of this invention.

Similar characters of reference are employed in all of the hereinabove described views, to indicate corresponding parts.

Referring now to said drawings, the reference character 6 indicates a lower body section of the vanity box and 7 an upper body section thereof. Said body sections are respectively provided along their meeting rear

edges with hinged knuckles 8 which interfit one with another to receive a hinge pin 9 whereby said sections are hingedly connected together so as to close one upon another. The periphery of the upper section 7 is provided, at the point thereof opposite its hinged connection with the lower body section 6, with a hinged lip 10 which is adapted to cooperate with a catch 11 provided at a corresponding point on the periphery of the lower body section 6. The hinged lip 10 and the catch 11 when engaged serve to interlock the sections 6 and 7 in closed relation.

A retaining frame 12 conforms to the interior of the lower body section 6 and has a central opening therein defined by the depending flange 13 which is arranged to rest upon the inner bottom surface of the lower body section. Retaining frame 12 fits snugly within the lower body section and is removably retained therein as by oppositely arranged bosses or projections 14 projecting inwardly from the side walls of the lower body section. Projections 14 engage the upper outer surface of the retaining frame, thereby holding this frame in position in the lower body section. The corner marginal edges of the retaining frame is provided with beveled or chamfered portions 15 which enable the insertion of a suitable instrument between the retaining frame and the inner wall of the lower body section, to thereby facilitate the removal of the retaining frame from this body section when desired. The depending flange 13 at the front and rear of the retaining frame is provided with spaced vertical slots 16 which extend inwardly for a distance from the marginal edges of this flange. Slots 16 snugly receive reduced extensions 17 provided on a pair of separating panels 18. Separating panels 18 have their upper marginal edges beaded over at 19 to provide a rounded upper edge portion having a double wall thickness. Separating panels 18 provide a cosmetic central receiving recess or chamber 20 and side recesses 21 and 22 at the sides of this central recess. A lip-stick receiving socket 23 having the form of a band bent to conform to the exterior surface of a lip-stick cover is posi-

100

tioned within the recess 20. Receiving socket 23 has outwardly projecting aligned bosses or teats 24 formed at the sides thereof which are pivotally mounted within apertures 26 5 provided in the separating panels 18. The abutting ends of the band forming the receiving socket 23 provide a longitudinal extending slot 27 which facilitates the insertion of the end portion of the lip-stick cover 10 28 into this socket. As the lip-stick cover 28 is pushed into the receiving socket 23, the slot 27 permits this socket to spread somewhat, thereby enabling the cover to be readily inserted and causing the socket to firmly 15 grip and hold the lip-stick cover 28. The lip-stick cover may as readily be removed from the socket by pulling outwardly upon the cover.

The lip-stick cover 28 is of the conventional 20 form and receives the lip-stick 29 and its holder 30 having the slide button 31. The pivotal connection of the socket 23 with the separating panels 18 enables the lip-stick and its holder to be readily turned outward- 25 ly of the receiving recess 20 of the lower body section. The receiving socket 23 is illustrated as provided with a spring flange 32 at one end thereof which flange engages retaining frame flange 13 when the lip-stick is positioned with- 30 in the receiving recess and it engages the bottom of the lower body section when the lip- stick is turned fully outwardly of the receiving recess; to thereby frictionally tend to re- 35 tain the lip-stick in either of these two limit- ing positions. If desired, the bottom edges of the separating panels 18 may be integral- 40 ly interconnected by a bottom web 33 as illus- trated in Fig. 4. The use of bottom web 33 serves to more firmly retain the panels 18 in their respective desired positions, but the use of this web is not essential to the construction of the novel vanity box of this invention.

The side recesses 21 and 22 are adapted to 45 receive suitable cosmetic agencies. Side re- cess 21 is illustrated as being employed for the reception of a compact rouge 34, which is frictionally retained within this recess, whereas side recess 22 accommodates a rouge 50 applicator 35. Compact rouge 34 is provided with an indenture 36 to facilitate the removal of this compact rouge from recess 21.

The retaining frame 12 is formed with hinge knuckles 37 at one end thereof to which 55 a double faced mirror 38 is hingedly connected by a hinge pin 30. Mirror 38 is adapt- ed to be folded into the body section 6 in over- 60 lying relation to the retaining frame or it may be turned outwardly of this body section into the external position shown in Fig. 1, in either of which positions it is adapted for use, since both of its faces are mirrored.

The upper body section 7 is illustrated as 65 provided with an inlay frame 41 that is re- tained within this body section by inwardly

directed bosses 43. Inlay frame 41 carries a powder compact 42. A powder puff or applicator (not shown) may be positioned upon compact 42.

In use, with the vanity box in closed position, the mirror 38 overlies retaining frame 12 and a powder puff (when used) is positioned between this mirror and cosmetic cake 42. In the event that it is desired at any particular application to use merely powder, it is not necessary to turn the mirror 38 outwardly of the body section 6. When it is desired to use the lip-stick 29 or the rouge cake 34, the mirror 38 may be turned outwardly of the body section 6 permitting access to these cosmetics. With the mirror 38 in its outer position shown in Fig. 1, the lip-stick and its cover may be readily swung outwardly by the fingers of one hand while the other hand is used to support the vanity box. The lip-stick and its holder may then be removed from the cover 28 for use and conveniently returned when desired into initial position shown in this figure.

It will be noted that the novel vanity box 90 of this invention is of simple construction and provides means for conveniently carrying a lip-stick, a rouge cake, a powder compact and applicators therefor as well as a mirror, all constructed and arranged so as to enable the use of the vanity box with a maximum of ease and convenience, and without the possibility of injury to the fingers or applicators. It will be apparent that the receiving socket 23 may be pivotally mounted at either end of the receiving recess 20, the same being illustrated in Figs. 1 and 2 as pivoted adjacent the hinged connection of the upper body section with the lower body section 6, and in Fig. 3 as adjacent the hinged connection of the mirror 38 with this lower body section. 95 100 105

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. 110 115

What is claimed is:

1. A vanity box comprising, a lower body section and a cooperating upper body section, a retaining frame positioned within said lower body section, a lip-stick, and socket means connected to said retaining frame and swivelly supporting said lip-stick thereupon so that said lip-stick may be turned inwardly or outwardly of said lower body section, said socket means comprising a unitary member with a split wall for resiliently gripping said lip-stick. 120 125

2. A vanity box comprising, a lower body section and a cooperating upper body section, a retaining frame positioned within said 130

lower body section, spaced separating panels connected to said retaining frame and dividing said lower body section into a plurality of cosmetic receiving recesses, and a lip-stick 5 swivelly mounted within one of said cosmetic receiving recesses and arranged to be turned outwardly of said recess for use, and means for releasably holding said lip-stick in either its innermost or outermost twined 10 positions.

3. A vanity box comprising, a lower body section and a cooperating upper body section, a retaining frame positioned within one of said body sections, spaced separating panels 15 connected to said retaining frame for providing cosmetic receiving recesses in said retaining frame body section, a receiving socket pivotally mounted within one of said receiving recesses, a lip-stick cover removably supported by said receiving socket, and a lip-stick 20 slidably received by said cover, the pivotal mounting of said receiving socket enabling said lip-stick to be turned outwardly of said recess for use.

4. A vanity box comprising, a lower body section and a cooperating upper body section, a retaining frame positioned within one of said body sections, spaced separating panels connected to said retaining frame for providing cosmetic receiving recesses in said retaining frame body section, said separating panels having bearing apertures therein, a lip-stick receiving socket having projections 30 thereon pivotally mounted in said bearing apertures and a lip-stick positioned in one of said cosmetic receiving recesses and having a cover removably supported in said lip-stick receiving socket, said lip-stick receiving socket having a split wall to facilitate the insertion 35 or removal of the lip-stick cover.

5. A vanity box comprising a lower body section and a cooperating upper body section, a retaining frame positioned within one of said body sections, spaced separating panels connected to said retaining frame for providing cosmetic receiving recesses in said retaining frame body section, said separating panels having bearing apertures therein, a lip-stick receiving socket having projections 45 thereon pivotally mounted in said bearing apertures, a lip-stick positioned in one of said cosmetic receiving recesses and having a cover removably supported in said lip-stick receiving socket, and a mirror hingedly connected to said retaining frame and foldable 50 into overlying closing relation to said cosmetic receiving recesses.

6. A vanity box comprising, a lower body section and an upper body section hinged together, a retaining frame positioned within said lower body section and having a central opening defined by a depending flange with slots therein, separating panels positioned within said lower body section and having 65 portions projecting into and frictionally en-

gaging the walls of said slots, said separating panels serving to divide said lower body section into a plurality of cosmetic receiving recesses, a lip-stick receiving socket pivotally mounted on opposed separating panels, a lip-stick positioned within one of said cosmetic receiving recesses and having a cover frictionally retained within said receiving socket, said lip-stick and its cover being turnable outwardly of said cosmetic receiving recess to a position substantially at right angles to said recess, and a spring flange formed on said lip-stick receiving socket and tending to hold said lip-stick cover in either its outermost or innermost position.

In testimony that I claim the invention set forth above I have hereunto set my hand this 16th day of October, 1929.
